UNITED STATES PATENT OFFICE.

JAMES JOSEPH KELLY, OF ALBANY, NEW YORK.

SHOW-CASE.

SPECIFICATION forming part of Letters Patent No. 378,594, dated February 28, 1888.

Application filed January 5, 1888. Serial No. 259,889. (No model.)

To all whom it may concern:

Be it known that I, JAMES JOSEPH KELLY, of Albany, in the county of Albany and State of New York, have invented a new and useful 5 Improvement in Cash and other Cases, of which the following is a full, clear, and exact description.

My invention relates to an improvement in cash and similar cases, and has for its object 10 to provide a strong, durable, and attractive case, readily opened and closed, and provided with a shelf operating in connection with the lid.

The invention consists in the construction 15 and combination of the several parts, as will be hereinafter fully set forth, and pointed out in the claims.

Reference is to be had to the accompanying drawings, forming a part of this specification, 20 in which similar letters of reference indicate corresponding parts in all the figures.

Figure 1 is a plan view of the case open and partly in section. Fig. 2 is a transverse section on line xx of Fig. 1 when the case is open; 25 Fig. 3 is a similar section on line xx of Fig. 1, the case being closed.

In carrying out the invention, A represents the body of the case, which is segmental in contour, provided with an inner fixed bottom, 30 a , and an outer bottom, a' , secured to the inner bottom with screws or equivalent devices, whereby it may be readily and conveniently attached or detached.

The outer bottom, a' , is provided centrally 35 the under face with a recess, b , extending from side to side, the walls whereof are grooved, adapted to receive a shelf, B, which shelf is purposed to slide in the recess b , being provided to that end with tongues at the ends entering the aforesaid grooves. The thickness 40 of the shelf is such as it will not touch or bind upon the object by which the case may be supported. The frame of the case, consisting of the aforesaid bottoms a a' and segmental end pieces, B', is completed by the addition of a 45 half-cover, C, rigidly secured in said end pieces. The end pieces, B', project beyond or above the fixed cover C, and the said extended portions are provided upon the inner side with a 50 groove, d , and below said groove at the open section of the case with an integral flange, d' ,

which flange terminates flush with the edge of the fixed cover C, as shown in Fig. 1. The end pieces are recessed each side of the center to receive glass panes D, said panes being held 55 in place by battens d' and entered through slots in the inner bottom. Thus the glass is sustained without putty and readily and conveniently replaced if broken. The grooved section of the end pieces also project out beyond the inner edge of the inner bottom in 60 similar manner as above the fixed cover.

The inner surface of the fixed cover C is preferably lined with a single piece of looking-glass E, and the upper surface of the inner 65 bottom, or a portion of said surface, may be likewise provided, if desired. Over the fixed cover and in the grooves d of the end pieces the second section, C', of the cover is adapted to slide, the tongues of which sliding section 70 of the cover (illustrated by dotted lines in Fig. 1) are of metal, preferably brass, being secured in any suitable or approved manner.

The sliding cover C' consists of a frame provided with an inserted glass pane, C'', and centrally to the rear of the said frame a cord or chain, E'', is attached, which cord, extending downward in a transverse groove produced upon the fixed cover, is secured at the other end to the rear of the sliding shelf B. 75

It will thus be observed that when the shelf B is drawn out the sliding cover is raised, and that when said cover is closed the shelf is drawn in.

By reason of the detachable bottom the sliding cover may be removed and cleaned in a 80 convenient and expeditious manner.

Having thus described my invention, what I claim as new, and desire to secure by Letters Patent, is—

1. The combination, with a case provided with a sectional cover, one part adapted to slide over the other, and a detachable auxiliary outer bottom, of a shelf sliding in said auxiliary bottom, and a cord or chain connecting said shelf and sliding cover, substantially as shown and described, whereby when the shelf is drawn out the sliding cover is raised, and vice versa, as set forth. 95

2. The combination, with a segmental case provided with a sectional cover, one fixed and the other sliding over the stationary section,

the said sliding section having metal tongues, of a detachable auxiliary bottom, a shelf sliding in said auxiliary bottom, and a cord or chain uniting the shelf and sliding cover of the 5 case, substantially as shown and described.

3. The combination, with a segmental case provided with lighted ends D, having grooves d upon the inner face and flanges d' below said grooves, a fixed sectional cover, C, and a 10 lighted cover, C', sliding over the said sta-

tionary cover, provided with metal tongues entering the grooves d, of an auxiliary detachable recessed bottom, a shelf sliding in said auxiliary bottom, and a cord or chain connecting the sliding cover and shelf, substantially as and for the purpose herein set forth. 15

JAMES JOSEPH KELLY.
